CARD SORTING MACHINE

Karl J. Braun, Brooklyn, N. Y., assignor to Remington Rand Inc., Buffalo, N. Y., a corporation of Delaware

Application April 24, 1937, Serial No. 138,699

4 Claims. (Cl. 209—110)

This invention relates to card sorting machines and particularly to those machines which are adapted to sort successive cards having the same designation into one pocket and to sort any card 5 having a different designation from the preceding and following cards into a second pocket.

This invention consists of converting the well known Powers tabulator base, shown and described in the Patent 2,044,119 to W. W. Lasker, filed May 19, 1931, into a two pocket card sorting machine. The machine will send successive duplicate cards into one pocket and will send all other cards into another pocket. The term "duplicate", as used above, applies to cards which 10 hold the same designatory punchings. The cards to be sorted are first placed in the usual receptacle and are fed, from the bottom, one at a time, by a power driven picker blade into the sensing chamber of the machine. Here the cards are sensed by a reciprocating pin box and are then fed into a retaining chamber. The usual "change of designation" mechanism is utilized to close the shutter on the foremost pocket of the sorter to allow any card which bears a different designation 15 from the preceding card and succeeding card to be deposited in the rearmost pocket. However, when two succeeding cards, having the same designatory punchings, are run through the machine, the first card is held in a retaining chamber while the second is being sensed and, since the "change of designation" mechanism is not affected by the second card, both cards are fed into the foremost sorter pocket. The operation 20 of the present invention is generally as follows:

The first card of any run is fed, by the aforementioned picker blade, into the sensing chamber and is sensed near the end of the first cycle of operation of the machine. On the second operating cycle, the first card is fed into a retaining chamber at the same time that the second card is being fed into the sensing chamber and both cards are then held in their respective chambers while the second card is being sensed. If the second card bears a different designatory 25 punching than the first then, on the third machine cycle, the first card will be fed into the rearmost sorter pocket, the second card will be fed into the retaining chamber and held there, and the third card will be fed from the card hopper into 30 the sensing chamber and held there. This procedure continues until a card enters the sensing chamber which bears the same designatory punching as the card which simultaneously enters the retaining chamber. When this occurs, 35 the cards are held until the end of the operating

cycle and then, on the next operating cycle, both cards are fed simultaneously into the foremost pocket of the sorter. If the next card bears the same designation as the two which were just deposited in the front sorter pocket, it will also be 5 sent, on the next operating cycle, into the front pocket. The timing and other mechanisms necessary to the operation of this machine will not be described here but will be described later in detail. 10

One object of this invention is to sort successive duplicate cards into one pocket of a two-pocket sorting machine.

Another object is to sort all cards other than succeeding duplicate cards into a second pocket 15 of a two-pocket sorting machine.

Other objects and structural details of the invention will be apparent from the following description when read in conjunction with the accompanying drawings wherein: 20

Figs. 1 and 2 together constitute a left hand sectional elevation taken substantially through the middle of the machine.

Figs. 3 and 4 together constitute a left hand elevation of the machine with the left hand cover 25 plate broken away to show the power transmission gearing.

Fig. 5 is a front elevation of the shutter control unit which controls the closing of the shutter on the forward sorter pocket and which controls the locking of the card stop associated with the retaining chamber, one screw head being omitted for the sake of clarity. 30

Fig. 6 is a top plan view of the shutter control unit shown in Fig. 5, two screw heads and 35 one spring stud having been omitted for the sake of clarity.

Fig. 7 is a left hand elevation of the shutter control unit.

Fig. 8 is a left hand sectional elevation of the 40 same unit taken substantially through the middle of the shutter control cam shaft along the line S—S of Fig. 6.

Fig. 9 is an exploded isometric view showing the 45 shutter control unit, the change of designation mechanism, and the main operating cams of the machine.

Fig. 10 is a front elevational detail of the stopping and starting toggles for the machine. 50

Fig. 11 is a fragmentary left hand detail elevational view of the stopping and starting mechanism for the machine.

Fig. 12 is a right hand detail elevation of the outer toggle. 55

Fig. 13 is a left hand detail elevation of the inner toggle.

Fig. 14 is a left hand detail elevation of the toggle breaking lever.

As will be seen from Figs. 3 and 4, the power drive of the sorter is the same as that shown in the Patent 2,044,119 to W. W. Lasker. The main operating shaft 1 is positively driven by the usual motor driven worm train shown in Fig. 6 of the above patent. As shown in Figs. 1 and 3, the usual picker knife 2 is moved rearward and forward once for every revolution of the main operating shaft 1 by an oscillating arm 3 and a connecting link 4. The arm 3 is securely fastened to a shaft 5 which extends through the left hand frame casting 6 (Fig. 3) of the machine. Fast upon the left hand end of shaft 5 is an arm 7, which is connected by a short link 8 to an arm 9 which arm is pivoted on a screw 10 fast to the left hand frame casting 6. This arm 9 bears, upon its right hand side, a follower roller (not shown) which is pressed by a spring 11 against a picker cam (not shown) which cam is mounted upon the main operating shaft 1. It will, therefore, be apparent that, for every revolution of the main shaft 1, the picker 2 (Fig. 1) will lead one card into a pair of continuously operating power-driven feed rolls 12 which will then feed the card into the usual sensing chamber as is clearly set forth in the Patent 2,044,119 to Lasker.

Stopping and starting mechanism

The stopping and starting mechanism for the machine is old and is not claimed herein but will be described in order to clarify the basic structure upon which the present invention is built. As will be seen from Figs. 3 and 10 to 13, inclusive, a clutch engaging and disengaging arm 13, which is the same as the arm 45 in Fig. 5 of the above mentioned Lasker patent, is mounted fast upon the left-hand end of a shaft 14 which runs from side-to-side across the front of the machine and acts to engage or disengage the old and well-known machine clutch which is not shown in the present application but which is clearly shown in Fig. 6 of the Lasker Patent 2,044,119. The clutch arm 13 is shown in detail with its associated operating toggles in Fig. 11 of the present drawings. In Fig. 3, a cam 15, mounted upon the left hand end of the main shaft 1 of the machine, normally lies in the position shown and carries, upon its periphery, a tooth 16 which is adapted to contact a follower roller 17, mounted upon the right hand side of an arm 18 which is pivoted at 19 to the casting 6. The arm 18 pivotally supports at its forward end, the lower ends of two push-links 20 and 21. The link 21 extends through a slot in the top of the frame casting 6 and is guided, by the slot, for vertical movement. It will, therefore, be evident that, for every revolution of the main operating shaft 1, the cam 15 will push the links 20 and 21 upward. As shown in Fig. 3, an interponent arm 22 is pivoted at 23 to the middle portion of an arm 24, which extends downwardly from its pivot point 23 and carries, at its bottom, a rightwardly bent off ear 26. The interponent arm 22 is formed with a raised portion 27, on its top side and a cut out portion 28 on its bottom side; and the pusher link 21, being in the same vertical plane as the interponent arm 22, travels up and down and carries the interponent arm 22 with it. Just above the interponent 22, is a lever 29 which carries, at its rear end, a lug 30 which is adapted to be acted upon

by the raised portion 27 of the interponent arm when it is desired to stop the machine. The lever 29 carries, at its forward end, a leftwardly bent lug 31 which overlies a lever 32 and which carries an adjusting screw 33 as is old and well known. Both levers 29 and 32 are pivoted upon a rock shaft 34 which is suitably supported by a casting screwed to the top of the left hand frame casting 6. The forward end of the lever 32 is pivoted to the top of an upright link 35, the lower end of which is pivoted by a short shaft 36 to the clutch arm 13. Thus, it will be seen that, if the interponent 22 is moved toward the rear of the machine and held there until the tooth 16, on the cam 15, strikes the follower 17, the push-link 21 will raise the interponent 22 and the raised portion 27 thereof will contact the lug 30 and swing the lever 29 clockwise (as seen in Fig. 3) which, in turn, will swing the lever 32 in the same direction and force the link 35 downward to disengage the clutch.

The means for causing the interponent 22 to assume its active position includes a push button 37 which is pressed toward the front of the machine by a coiled spring (not shown) and which has a rearwardly extending stem 38. As will be seen from Figs. 3 and 11, the rear end of the stem 38 pivots the forward end of a link 39 which is pivoted at its rear end to a rock lever 40 which is pivoted, at 41, to the left hand frame casting 6. Pivoted to the upper end of the rock lever 40, at 42, are two adjacent levers 43 and 44. The forwardly extending lever 43 is formed with a hook at its forward end and is tensioned clockwise (Fig. 3) by a spring 45 which is anchored at its upper end to the lever 43 and at its lower end to a lug 46 on the link 35. At its rear end, the lever 43 is formed with a leftwardly bent lug 47 which underlies the bellcrank 44 and limits its counter-clockwise movement about the pivot 42. A spring 48, anchored at its upper end to the lever 43 and at its lower end to the bellcrank 44, tends to constantly keep the bellcrank against the lug 47. The rear end of the bellcrank 44 is formed, as shown, with a notch 49 for engagement with the ear 26 of the arm 24 and it will be seen that the spring 45 tends to rock both levers 43 and 44 clockwise, as shown in Fig. 3, so that the notch 49 will clear the ear 26 when the machine is being started. When, however, the machine is operating, the levers 43 and 44 will be rocked counter-clockwise far enough so that the notch 49 will be in a position to contact the ear 26 and move the interponent 22 toward the rear to stop the machine, as will now be explained.

Adjacent the right hand or inner side of the link 35 are two toggles 50 and 51 as will be clearly seen in Figs. 10, 11, 12 and 13. The outer toggle 50, which lies flush with the right hand side of the link 35, consists of two short links 53 and 54 which are pivoted together at 55. The upper link 53 of the outer toggle 50 is pivoted at 52 to the link 35. The lower link 54 of outer toggle 50 has, in its bottom, a hole through which passes the short shaft 36. This shaft 36 (Fig. 10) passes leftwardly through the link 54 and, thence, through a slot 56 in the link 35 and is held against rightward movement by a keeper 57. A spring 58 tends constantly to keep the toggle 50 in its straightened position, in which position it limits against a pin 59 held on the link 35 as shown in Fig. 12. The top end of the upper toggle link 53 is made with a slot 60 which embraces a pin 61 (Fig. 10) which pin is fast in the 75

left hand face of a toggle breaking lever 62 which carries a slightly larger pin 63 on its right hand face. The inner toggle 51 is somewhat similar to the outer toggle. The upper link 64 of this toggle (see Fig. 13) is formed with an offset finger 65 and is pivoted to a lower link 66 by a headed rivet 67. A spring 68, similar to the spring 58, tends constantly to hold the inner toggle 51 in its straightened position wherein a nose 69, on the upper link 64, limits against a pin 70 held on the left hand face of the lower-link 66. The upper link 64 of the inner toggle 51 is pivoted at 71 to a frame stud 72 which is suitably fastened to the lefthand frame plate 8 of the machine. The toggle breaking lever 62, as will be seen from Fig. 10, lies directly between the outer toggle 50 and the inner toggle 51 and is pivoted upon the same frame stud 72 as the inner toggle link 64 and it will also be seen that if the lever 62 is swung counter-clockwise as seen in Fig. 3, the pins 61 and 63 will act to break both toggles. Fig. 3 shows the normal, unoperated position of the machine and Fig. 10 shows the normal or unoperated position of the toggle assembly, while Fig. 11 shows the toggles in the position they assume when the machine is operating. When the machine is running and the clutch is engaged, the clutch spring (not shown herein but designated by the reference numeral 34 in Fig. 6 of the drawings of the Patent 2,044,119) holds the inner toggle 51 broken as is shown herein in Fig. 11. The outer toggle is straight and, since this is so, the link 35 is in its upper position with the lower end of its slot 58 occupied by the short shaft 38. Since the link 35 is in its upper position a pin 73, fast on its right hand side, engages the under side of the hooked lever 43 and holds it in such a position that, if the stopping and starting button 37 were pushed in, the hook on the lever 43 would not engage the nose of the toggle breaking lever 62 or affect either toggle. However, the rearward movement of the lever 43 would (Fig. 3) move the notch 49, in lever 44, against the ear 26 of arm 24 and move the arm 24 a small distance rearward. This would move the raised portion 27, of the interponent 22, under the lug 30 on the lever 29 and, when the cam 15 next lifted the link 21, the levers 28 and 32 would be rocked a small amount clockwise and would push down the link 35. At this time the outer toggle 50 is straight and the shaft 36 is still in the lower end of the slot 56 in link 35 and, consequently, when the link 35 is pushed down, the straightened outer toggle 50 is also forced down thus pushing down the shaft 36 which disengages the clutch (not shown) and allows the spring 68 (Fig. 11) to straighten the inner toggle 51. This toggle 51 will now hold the clutch disengaged until the starter button 37 is again pushed in. Since the link 35 is now in its lower position, the pin 73, thereon, will allow the hooked lever 43 to assume its normal position. In its normal position the lever 43 is so located that, if the starter button 37 were pushed in, its hooked portion would contact the nose of the toggle breaking lever 62 and break both toggles. In its normal position the lever 43 would also be holding the spring pressed lever 44 in such a position that the notch 49, thereon, would clear the ear 26 on lever 24 as is shown in Fig. 3. When both toggles 50 and 51 are broken, as is the case when the machine is being started, the clutch spring overcomes the tension of the spring 68 and the inner toggle 51 remains broken as shown in Fig. 11. However, the outer

toggle 50 remains broken only for an instant. The action of its spring 58 immediately restores it to its normal position and this now raises the link 35 to its upper position shown in Fig. 11.

In summation, when the machine is in normal unoperating position, both toggles must be broken to start it and the inner toggle 51 then remains broken but the outer toggle 50 immediately snaps to normal, unbroken, position raising the link 35 and the interponent 22 remains in its normal inactive position. To stop the machine, the button 37 is pushed in again and, though the toggles are unaffected by this action, the interponent is moved to its active position. When the cam 15 next moves up the push link 21, the levers 29 and 32 act to push down link 35, thus straightening the inner toggle 51, which position is shown in Figs. 1 and 10, to disengage the clutch.

Card transport train

As will be seen from Figs. 1 and 2, the punched cards are fed, by the aforementioned power feed rolls 12, into the sensing chamber 75 and, after sensing has been accomplished, they are fed, in the usual manner, into a train of transport rolls 76, 77, 78, and 79 which rolls convey the cards into either of two sorter pockets 80 and 81. The upper rolls 76, 77, 78, and 79 are spring pressed skid rolls, as shown, but the lower rolls 76, 77, 78, and 79 are power driven. The lower roll 76 is positively driven from the main worm drive on the right hand side of the machine, and upon the shaft 76A, as shown in Fig. 2, is fastened a bevel gear 82 which rotates with the shaft 76A and meshes with a similar bevel gear 83 mounted fast upon a shaft 84. This shaft carries three other bevel gears 85, 86, and 87 which are identical with the gear 83. The gears 85, 86, and 87 mesh with identical bevel gears 88, 89, and 90, respectively, which are fast upon the right hand ends of the shafts 71A, 78A, and 79A respectively. It will thus be seen that, as long as the clutch is engaged, the conveyor or transport rolls 76, 77, 78, and 79 will be positively driven and each will be driven an identical amount.

Change of designation mechanism

Referring particularly to Figs. 1, 2, and 9, the sensing of a card is done by the usual sensing mechanism shown in Fig. 10 of Lasker's Patent 2,044,119 which is identical to the mechanism shown in Figs. 1 and 2 of the present application. A pin box, designated generally by the reference character 91 in Figs. 1 and 2, holds forty-five rows of pins 92, there being twelve pins in each row. Each pin 92 is formed with a tapered point and has, at its middle, a small leftwardly extending locking pin or extrusion 93. The locking pins or extrusions 93 coact with the usual cam actuated locking slides 94 and those pins which pass through holes in the card being sensed are locked in position in a manner which is old and well known in the art and fully described in said patent. The pin box 91 is reciprocated by an eccentric 95 and strap 96 and is moved down and up once for every revolution of the main operating shaft 1. The upper pins 97 are also provided with small pins or extrusions 98 and 99 which coact with sets of slides 100 and 101 respectively.

The lower slides 100 are locking slides and are spring pressed toward the rear of the machine by leaf springs 102 and all the locking slides are pressed, against the tension of springs 102, toward the front of the machine by a retract bail bar 103.

near the end of each operating cycle. The retract bail bar 103 is held by a pair of depending arms 104 which are pivoted and made fast to a rock shaft 105 which is journaled in suitable supporting brackets 106, the left-hand one of which is shown in Figs. 3 and 9. From Figs. 3 and 9, it will be seen that the rock shaft 105 is operated by the cam 15 acting through the pusher link 28 which moves a rock lever 107 which is fast upon the left hand end of the shaft 106. A spring (not shown) tensions the rock arm 107 so that it constantly touches and follows the movement of the push link 20.

As shown in Figs. 1, 2, and 9 the "change of designation" slides 101 are not tensioned by any springs but cooperate with a set of interponent members 108 to move a "change of designation" bail bar 109. The interponents 108 are manually depressable, by their finger pieces 110, from their normal or upper positions shown in Fig. 1, to their active or lower positions shown by the leftmost interponent in Fig. 9; and it will be understood that there is one interponent member 108 for each "change of designation" slide 101. Hence, it will be seen that, if the interponents 108 are set in their lower or active positions, when the designatory punching of a card being sensed differs from the punching of the preceding card, the "change of designation" slide or slides 101 (depending on the number of columns being used for sensing designatory matter) associated with these punchings will be moved toward the front of the machine and will push forward the respective interponent member or members 108 which, in turn, will swing the bail bar 109 toward the front of the machine or counter-clockwise as seen in Fig. 1. As can easily be seen from Fig. 9, the bail rod 109 is supported between two depending arms 111 which are made fast, at their upper ends to a rock shaft 112 which is supported at its left hand end in a casting 113 which is shown in Figs. 3, 5, 6, and 8. The right hand end of the rock shaft 112 is supported by a bracket (not shown) which is mounted on the top of the right-hand frame casting which is similar to the boxlike casting 6. Fast upon the extreme left hand end of the shaft 112 is mounted a finger 114 which in its normal position, as is shown in Figs. 5, 6, 7, 8, and 9, rests against a stud 115 which is riveted to a latch 116 on the shutter control unit now to be described.

Shutter control unit and card-stop mechanism

Figs. 5, 6, 7, 8, and 9 show the shutter control unit which is mounted and supported upon the casting 113 previously referred to. Referring for a moment to Figs. 1, 2, 3, and 4, it will be seen that, mounted on a shaft 117, is a card gate or shutter 118, which normally stands open as is clearly shown in Fig. 2. Fast upon the left-hand end of this shaft 117, there is rigidly secured a bell-crank lever 119, the upper arm of which is pivoted at 120 to the rear end of a link 121 which has, in its forward end, a slot 122 in which rides a pin 123 which is carried in the lower part of the left hand face of a latch 124, pivoted at 125 to the left hand frame plate 131 of the machine. The latch 124 is formed with a flat top edge 126 and a flat front edge 127 both of which edges cooperate with a pin 128, held in the rear part of a centrally mounted lever 129 as is shown in Fig. 4. As is clearly shown in Figs. 2 and 4, the lever 129 (Fig. 4) is made fast upon the extreme left hand end of a card stop operating shaft 130 which extends laterally across the rear of the

machine and is journaled in the left and right hand rear frame plates 131 (Fig. 4) and 132 (Fig. 2) respectively. Just inside the frame plates 131 and 132 and fast upon the shaft 130 are two rearwardly extending arms 133 (the right hand one of which is shown in Fig. 2), which are pivoted at their rear ends to a card stop plate 134 which is mounted for vertical sliding movement upon the rear face of a cross bar 135 which is fastened at both ends to the frame plates 131 and 132. Screwed to the inside of each of the frame plates 131 and 132, is a bar 136 (the right hand one of which is shown in Fig. 2) and upon the top of these bars 136 is fastened a guide plate 137, which is the upper plate of a card retaining chamber, and two small guide strips 138 (Fig. 2). Spaced apart from and supported by the upper guide plate 137 of the card retaining chamber, is a plate 139 which is the lower guide plate of the card retaining chamber and which is fastened to the upper guide plate 137 by screws, not shown herein.

Returning to Figs. 3 and 4, it will be seen that the forward end of the card stop actuating lever 129 holds a leftwardly protruding pin 140 which rides in a slot 141 cut in the lower end of a link 142 the upper end of which is pivoted to a rock lever 143 and 144. The rock lever 143, as will be more easily seen from Fig. 9, extends toward the rear of the machine and is made fast to the same shaft 151 as a rock arm 143A which operates the usual card stop (to be described hereinafter) for the sensing chamber through a link 145, etc. The top of the link 145 is pivoted upon the left-hand side of the rock lever 143A, and the link 142 (Figs. 3 and 4) is pivoted upon the left-hand side of the rock arm 143. Thus, it will be seen that the rock levers 143 and 143A act to open and close the card stops for both the sensing chamber and the retaining chamber simultaneously as will be more fully explained hereinafter.

Referring to Figs. 2, 3, and 9 together, it will be seen that the main operating shaft 1 holds a card stop actuating cam 146 which acts, near the middle of each operating cycle of the machine, upon a follower roller 147 which is held upon the left hand side of a lever 148, and lowers and raises a link 149 which is pivoted, at its lower end, to the forward end of the lever 148 and at its upper end to the end of a rock arm 150 which is fast upon a shaft 151 journaled in suitable brackets supported on the framework of the machine. On the right hand end of the shaft 151 is fastened the rearwardly extending rock lever 143 and also the lever 143A, the latter pivotally supporting the upper end of the link 145 the lower end of which is pivoted at 152 to the rear end of a lever 153 (see Fig. 9 only) made fast to the left-hand end of a shaft 153A which is journaled in brackets (not shown) supported upon the left and right hand frame castings. The forwardly extending end of lever 153 lies in a slot 154 which is cut in the left hand edge of a card stop supporting strip 155, which strip is mounted for vertical sliding movement upon two support bars 156 (shown only in Fig. 2). Bars 156 extend laterally across the rear of the pin box and are supporting and guiding bars for the upper pin box assembly as is old and well known. On the right hand end of the shaft 153A, there is fastened a forwardly extending lever (not shown herein but designated by the reference character 241 in Fig. 21 of the Patent 2,044,119 to W. W. Lasker) which extends into a slot in a strip which is identical with the strip 155 shown herein in Fig. 9. The two strips 75

155 are bent rearwardly at their bottoms and are securely fastened to a card stop 157 which is shown as an angle bar in Fig. 9 and which is the well known card stop for the sensing chamber of the machine. From the foregoing it will be seen that the sensing chamber card stop 157 (Fig. 9) and the retaining chamber card stop 134 (Fig. 2) may be operated simultaneously by the rock arms 143 and 143A (Figs. 3, 4, and 9). At certain times, 5 which will be fully set forth hereinafter, the card stop 134 for the retaining chamber will be held inactive while the sensing chamber card stop 157 is in its downward or active position and it is for this reason that the pin and slot connection 10 140—141, shown in Fig. 4, is made between the lever 129 and the link 142. It will be recalled that as seen in Figs. 3, 4, and 9, the bell-crank 119 is fast upon the shaft 117 which is the pivot shaft for the card gate or shutter on the front sorter 15 pocket 81. The bell-crank 119 is pivotally connected at 158 to the lower end of a curved link 159, the upper end of which is pivotally connected at 160 to the rear end of a rearwardly extending rock lever 161 mounted upon and rigidly secured 20 to the right-hand end of a rock shaft 162. Fast upon the left-hand end of the rock shaft 162, is mounted an arm 163 which carries upon its left-hand face an anti-friction roller 164 which is adapted to follow the periphery of a cam 165 25 having four equally spaced grooves cut therein. 30

From the foregoing, it will be seen that when the shutter control cam 165 rests in its normal position, shown in Figs. 3, 5, 6, 7, and 9, the roller 164 rests in one of its peripheral grooves and, 35 consequently, the lever 161 is holding the link 159 (see Figs. 3 and 4) in such a position that the latch 124 (Fig. 4) is in its normal upright position wherein its top edge 126 lies directly under and in the path of the pin 128 on the lever 129 and is in position to lock the card stop 134 40 (Fig. 2) in its upper inactive position. It will further be seen that the bell-crank 119 (Fig. 4) is in such a position that it is holding open the card gate, or shutter 118, in the position shown in Fig. 2. It will, therefore, be seen from Figs. 2, 3, and 4 that, if the shutter control cam 165 were swung one eighth of a revolution clockwise, as seen in Fig. 3, so that the roller 164 were cammed up onto a high part of the periphery of cam 165, the roller 164 would swing the shaft 162 slightly counter-clockwise, as seen in Fig. 3, which, in turn, would swing the rock arm 161 in the same direction and would push the link 159 toward the rear of the machine. This would swing the bell-crank 119 clockwise, which would 50 push the link 121 toward the front of the machine and this would swing the latch 124 counter-clockwise far enough to remove the edge 126 from the path of the lever 129 so that the shutter 118 (Fig. 2) would be closed and the card stop 134 (Fig. 2) would be free to operate simultaneously with the card stop 157 (Fig. 2) associated with the sensing head. 55

The means for actuating the above described shutter control and card stop control mechanism will now be described in detail. As seen in Figs. 5, 6, 7, 8, and 9, the entire shutter control unit is mounted upon the casting 113 which is omitted in Fig. 9 for the sake of clarity. The casting 113 holds upon its left-hand face a fixed shaft 166 upon which is mounted for rotation a sleeve 167 which is formed integral with a large spacer collar 168 (Figs. 5 and 6) in its exact middle. Fixed upon the left-hand side of the sleeve 167 is a ratchet disc 169, a spacer collar 170 and the afore- 70

mentioned shutter control cam 165. Fixed upon the right-hand side of the sleeve 167 is a ratchet disc 171 which is identical to ratchet disc 169, a spacer collar 172 and a detent cam 173, which cam is identical in contour to the shutter control 5 cam 165. The cams 165 and 173 and the ratchet discs 169 and 171 are all fixed to each other and to the sleeve 167 by two long rivets 174 and 175 which run through the entire assembly including the central spacer collar 168 which is an integral 10 part of the sleeve 167 as previously mentioned. The exact angular positions of the two cams and two ratchets, in relation to each other, will be described accurately hereinafter. 15

The ratchet discs 169 and 173 are operated by 20 rock arms 176 and 177, respectively, (pivoted upon a stub shaft 176A Fig. 8) which is fast in the left-hand face of the casting 113. Arms 176 and 177 are spring pressed counter-clockwise, as viewed from the left-hand side of the machine, 25 and are actuated by a link 178 whose upper end has riveted thereto an offset branch 179 as is clearly shown in Fig. 9. The link 178 is operated from the main operating shaft 1 by a cam 179A which acts upon a follower roller 180 which is 30 fixed upon the left-hand face of an arm 181 pivotally mounted upon the left-hand frame casting 6 and which (Fig. 3) is constantly urged clockwise by a spring 182 anchored, at its upper end, to a stud carried upon the left-hand face of 35 the arm 181 and, at its lower end, to a stud carried upon the left-hand face of the arm 148. As was previously explained, arm 148 is pivoted to the link 149 (see Fig. 9) which operates the card stops for the machine. Returning to Figs. 5 to 9 40 inclusive, it will be seen that (as is particularly shown in Fig. 7) the left-hand ratchet operating arm 176 is normally held in its upper position by the latch 116 which is pivotally mounted upon the left-hand end of a shaft 201 fast in the 45 left-hand face of the casting 113. Pivoted, upon the right-hand side of the ratchet operating arm 176, is a pawl 184 which has a forwardly extending tooth 185 adapted, at certain times to act upon the teeth of the ratchet disc 169 on the sleeve 167, upon which it is angularly mounted one eighth of a revolution clockwise from 171 as seen in Figs. 7 and 8. A spring 186, which is anchored at its forward end to a stud 187, carried upon the right-hand face of the 50 arm 176, and at its rearward end to a stud 188 carried upon the right-hand face of the pawl 184, tends constantly to draw the tooth 185, of the pawl 184, against the ratchet 169. A pin 189 is riveted to the top of the pawl 184 and protrudes from the right hand face thereof. Thus, 55 it will be seen that should the latch 116 be swung counter-clockwise as seen in Fig. 7, the ratchet operating arm 176 would swing counter-clockwise until it came to rest upon the top of the push link 178 and, in this position, the tooth 185 on the pawl 184 would no longer be contacting one of the four, evenly spaced, high parts of the ratchet 169 but would be resting against one of the four low parts or ratchet teeth. It will further be seen that, since the latch 116 is always released (when it is released), near the end of a machine cycle, then upon the following machine cycle, the pusher link 178 will be moved upward near the middle of the cycle and will move the arm 176 60 and the pawl 184 up with it which will revolve the ratchet disc 169 one-eighth of a turn clockwise (as viewed in Fig. 7). 65

Fig. 8 shows the right-hand ratchet disc 171 and the detent cam 173. As will be seen there, 75

the right-hand ratchet operating arm 177, which is pivoted upon the same shaft 178A as the arm 176, is identical in shape and size with the arm 176. A collar 190 spaces the two arms apart as is shown in Figs. 5 and 6. Returning to Fig. 8, it will be seen that, mounted pivotally upon the left-hand face of the arm 177, is a pawl 191 which has a forwardly extending tooth 192 adapted, at certain times (to be fully set forth later), to engage and move the ratchet disc 171 one-eighth of a revolution, just as the left-hand pawl 184 may engage and move the left-hand ratchet disc 169. The pawl 191 is constantly urged toward the ratchet disc 171 by a spring 193 the forward end 10 of which is anchored to a stud 194, carried by the arm 177, and the rearward end of which is anchored to a stud 195, carried upon the pawl 191. In normal position, the tooth 192 of the pawl 191, lies against one of the low portions of the ratchet disc 171. The arm 177 is not held by any latch and it rides up and down, with the movement of the pusher arm 179, once for every machine cycle. Normally, it rests, as shown, in its lowest position.

25 It will be noted here that the pin 189, which is carried by the pawl 184, extends leftwardly into the plane of the pawl 191 and at certain times (to be described hereinafter), acts upon the pawl 191 to prevent the tooth 192 thereof from engaging and moving the associated ratchet disc 171. The detent cam 173 normally stands as shown in Fig. 8, with one of its high parts supporting an anti-friction roller 196 which is pivotally mounted upon the right-hand side of the 30 rearwardly extending arm 197 of a bell-crank to whose upright arm 198 is anchored the forward end of a spring 199, the rear end of which is anchored to a short upright arm 200 fastened to the shaft 162 by a screw collar. The detent bell-crank 197—198 is loosely pivoted upon the stub-shaft 201, fast in the left-hand side of the shutter control casting 113, and is spaced from the latch 116 (shown in Figs. 5, 6 and 7) by spacer collars.

40 45 *Machine operation*

The stack of cards to be sorted for duplicates is first run through a standard sorter, and is sorted sequentially so that all cards bearing identical designation punchings will be placed next to each other. The stack of cards, thus prepared, is then put into the magazine of the present machine and the motor switch (not shown) is turned on. The operator then presses the starting button (Fig. 3) which breaks the toggle mechanism shown in Fig. 3 and in detail in Figs. 10-14. This allows the clutch to engage and the main shaft 1 begins to revolve. During the first half cycle of the 50 main shaft 1, the reciprocating pin box 91 is lowered and the picker 2 pulls the first card (or bottom card) into the foremost set of feed rolls 12 whence it is immediately conveyed into the sensing chamber, at which time the card stop 4 for the sensing chamber comes into its lower or active position and holds the first card in position to be sensed as it is shown in Fig. 2. On the 55 second half of the first operating cycle, the picker knife returns to the Fig. 1 position and the reciprocating pin box 91 is drawn upward to the 60 position shown in Figs. 1 and 2. Near the end of the cycle, the lower pins 92 enter the designation holes in the card and push up the upper pins 97 which, through their extrusions 99, move the "change of designation" slides 101 toward the 70 front of the machine. The interponents 108, in

the designation columns, having been previously manually set into their lower or active positions, lie between the forward ends of the "change of designation" slides 101 and the bail bar 109 and consequently, when the slides 101 are pushed forward by the upper pins 97, they push the interponents toward the front of the machine and this rocks the bail bar 109 toward the front of the machine or counter-clockwise (as seen in Fig. 1) about its pivot shaft 112. As seen in Fig. 9, the 10 shaft 112 extends laterally across the front of the machine and, when it is rocked by the bail bar 109, the finger 114 trips the latch 116 and allows the arm 176 to swing, under tension of its spring, and lower the pawl 184 so that it rests on one 15 of the low parts of the ratchet disc 169 in position to turn said ratchet disc on the next cycle. During this first cycle, the right-hand ratchet operating arms 176 and 177 are now in their 20 lower positions and resting respectively upon the top of the link 178 and the offset branch 179. 25 The second operating cycle begins and it will be assumed that the second card contains different designation punchings than the first. In the first half of the second cycle, the pin box is lowered and the picker feeds the second card into the 30 sensing chamber. Simultaneously, the first card is rolled into the retaining chamber (Fig. 2) and both card stops come to their lower or active positions to retain the cards in their respective chambers. As seen in Fig. 9, the card stop cam 146 and the ratchet feed operating cam 179A are keyed to the main shaft 1 and turn together. These two cams are so positioned that the cam 146 operates to open the card stops after the cam 179A has actuated the ratchet operating arms 40 45 and it will, therefore, be seen that, before the middle of the second operating cycle, the cam 179A has reached its high point and the ratchet operating arms 176 and 177 have been pushed up by the link 178. The result of this is that, 50 since the arms 176 and 177 were moved up together, the pin 189, in the pawl 184, held the pawl 191 out of active engagement with its ratchet disc 171 and the tooth 185, of pawl 184, turned the ratchet disc 169 one-eighth of a revolution. 55 From the foregoing it will be evident that if the left-hand ratchet operating arm 176 remains latched by the latch 116 (as is the case when duplicate cards follow each other through the sensing chamber) the arm 177 will move its pawl 191 up and down and the pawl will be free to act upon the ratchet disc 171 but, whenever the latch 116 is tripped and the pawl 184 snaps down to its lower position, (as is the case where cards with varying designatory punchings follow each 60 other through the sensing chamber) the pin 189 will hold the pawl 191 inactive during the next cycle. It will be remembered that at the middle of the second operating cycle the pawl 184 has rotated the ratchet disc 169 one-eighth of a revolution. Consequently, the shutter control cam 165 has also been rotated one-eighth of a revolution and this has cammed the follower roller 164 up onto one of its high parts to act (as previously explained) through the arm 163, shaft 162, arm 161, link 159 and bell-crank 119 (Fig. 4) to close the card gate or shutter on the pocket 81 and to remove the latch 124 from the path of the card stop lever 129. Thus, it will be seen that, at the 70 middle of the second operating cycle, both card 75

stops 134 and 157 (Fig. 2) are in their upper inactive positions and the first card is being fed into the retaining chamber while the second card is being fed into the sensing chamber. In the 5 last half of the second cycle the two card stops 134 and 157 close simultaneously to hold the first card in the retaining chamber and the second card in the sensing chamber after which the pin box moves up and senses the second card in the 10 usual manner and finding different designatory punchings, the "change of designation" slides 101 are again moved toward the front of the machine which again trips the latch 116, shown in Fig. 9 and allows the left-hand ratchet operating arm 176 to drop its pawl 184 as has been explained.

It will thus be seen that, as long as cards with varying designations punched therein are fed through the sensing chamber, the "change of designation" mechanism will trip the latch 116 (Fig. 9) and the shutter or card gate 118 will remain closed so that the cards will all be fed into the rear sorter pocket 80; and it will further be noted that there will always be one card held 25 in the retaining chamber while another card is being sensed in the sensing chamber.

Assuming that there are two cards in the chambers, as above, and that they hold different designatory punchings, near the middle of the 30 next operating cycle, which for the sake of illustration will be the tenth machine cycle, the card in the retaining chamber is rolled into the rear sorter pocket 80, the card in the sensing chamber is rolled into the retaining chamber, and a 35 new card is fed into the sensing chamber and it will be assumed that the card, which now rests in the sensing chamber, bears identical designatory punchings to the card which is in the retaining chamber. When this happens, the 40 "change of designation" mechanism will not be affected and consequently the left-hand ratchet operating arm 176 (as seen in Fig. 9) will be latched away from its pusher link 178 by the latch 116. As will be remembered, however, the assembly which includes the two ratchets 169 and 45 171 and the two cams 165 and 173, will not be in the Fig. 9 position but will be one-eighth of a revolution away from it so that the roller 164 is up on a high part of cam 165, pawl 184 is in its 50 upper position but resting against a low part of the ratchet 169, the pawl 191 is in its lower position and resting against a low part of the ratchet 171, and the detent roller 196 is resting in a low 55 part of the detent cam 173, as sensing takes place. It will here be noted that, since the pawl 184 is being held in its upper or inactive position by latch 116, the pin 189 thereon has allowed the pawl 191 (which is in its lower or active position) to ride in against a low part of the ratchet 60 disc 171 and it will further be understood that, on the next or eleventh operating cycle, the pawl 191 will engage and move the ratchet disc 171 one-eighth of a turn which will move the entire 65 shutter control assembly to the Fig. 9 position in which position the shutter 118 will be open as shown in Fig. 2. Since the shutter is opened before the middle of this eleventh cycle, and, since the link 159 (Fig. 9) has been returned to its original position, shown in Fig. 4, before the card 70 stop mechanism has been actuated, it will be understood that the front edge 127 of the latch 124 (shown only in Fig. 4) will be resting against the pin 128 on the lever 129 and that the latch 124 will be heavily tensioned against said pin. 75 When, near the middle of the eleventh cycle, the

card stop mechanism previously described raises the card stops, the latch 124 immediately snaps under the pin 128 and prevents the card stop 134 from closing. Thus, in the eleventh cycle, the card which is in the retaining chamber is rolled into the front sorter pocket 81 and the card which is rolled from the sensing chamber passes through the retaining chamber and into the pocket 81. It will thus be seen that all subsequent cards bearing the same designation punchings as the two 10 which rest in the front sorter pocket 81 will be conveyed from the sensing chamber direct to the pocket 81. Therefore, all cards which bear the same designation punchings as the preceding card will be deposited in the front pocket 81 and 15 all cards whose designatory punchings vary from the preceding and succeeding cards will be fed into the retaining chamber and held there until the next operating cycle when they will be deposited in the rear pocket 80. 20

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed. 25

What I claim as new, and desire to secure by Letters Patent is:

1. The combination of two card-retaining chambers, card sensing means, a change-of-designation device, means for feeding cards to one of said chambers and thence to the other of said chambers and thence away from the last mentioned chamber, a respective card stop for each of said chambers, operating mechanism common to both card stops, a latch for holding one of said card stops against operation by said operating mechanism, and means under control of said change-of-designation device for enabling and disabling said latch. 35

2. In a machine of the class described, the combination of card sensing means, a card retaining chamber, a pair of receiving stations, transporting means for feeding cards to said sensing means and thence to said retaining chamber and thence to said receiving stations, means for arresting a card in cooperative relation to said sensing means, means for arresting a card in said retaining chamber, a card deflector movable to different positions to guide cards to one and the other of said receiving stations, and means whereby said sensing means may control 50 the last mentioned card-arresting means and concomitantly control the positioning of said card deflector. 55

3. In a machine of the class described, the combination of card sensing means, a change-of-designation device, a card retaining chamber, a plurality of receiving stations, transporting means for feeding cards to said sensing means and thence to said retaining chamber and thence to said receiving stations, means for arresting a 60 card in cooperative relation to said sensing means, means for arresting a card in said retaining chamber, a cam, means operable by said cam to enable and disable the last mentioned card-arresting means, and means under control of said 65 change-of-designation device for operating said cam. 70

4. In a machine of the class described, the combination of card sensing means, a change-of-designation device, a card retaining chamber, 75

a plurality of receiving stations, transporting means for feeding cards to said sensing means and thence to said retaining chamber and thence to said receiving stations, means for arresting a card in cooperative relation to said sensing means, means for arresting a card in said retaining chamber, a card deflector movable to different positions to guide cards to one and an-

other of said receiving stations, a cam, means operable by said cam to enable and disable the last mentioned card arresting means and to concomitantly position said deflector, and means under control of said change-of-designation device for operating said cam.

KARL J. BRAUN.
